UNITED STATES PATENT OFFICE.

FRANCIS JERDONE, JR., OF TOLEDO, OHIO, ASSIGNOR TO THE WILLYS-OVERLAND COMPANY, OF TOLEDO, OHIO, A CORPORATION OF OHIO.

AUTOMATIC TAKE-UP DEVICE.

1,421,784.

Specification of Letters Patent. Patented July 4, 1922.

Application filed February 24, 1919. Serial No. 278,770.

To all whom it may concern:

Be it known that I, FRANCIS JERDONE, Jr., a citizen of the United States, residing at Toledo, in the county of Lucas and State of Ohio, have invented certain new and useful Improvements in Automatic Take-Up Devices, of which I declare the following to be a full, clear, and exact description.

My invention relates to an automatic take-up device and has for its object to provide improved means adapted to automatically compensate for lost motion between two or more co-operating parts or mechanisms.

A further object of the invention is to provide, between the cam shaft and exhaust valve of an internal combustion engine, an improved automatic take-up device adapted to compensate for lost motion between said parts, suitable means being also provided for conveying lubricating material from the crank case of the engine to said take-up device.

Another object of the invention is to provide between the push rod and valve stems of an internal combustion engine a spring actuated spacing member having inclined faces engaging correspondingly inclined faces on the push rod and stem and tending to constantly move said parts in opposite directions.

To these and other ends the invention comprises certain novel features of construction and arrangement of parts as will be hereinafter more fully described and claimed, it being understood that the invention is susceptible to certain modifications not shown in the drawings which will be comprehended by the appended claims.

A structure constituting one embodiment of my invention is shown in the accompanying drawings forming a part of the specification in which:

Figure I is a fragmentary sectional elevation illustrating the application of one form of the invention to the valves of an internal combustion engine.

Figure II is an inverted plan of the valve stem seat shown in Figure I.

Figure III is a top plan view of the cam shown in Figure I.

Figure IV is a fragmentary sectional elevation of a modified form of the invention.

Figure V is a detail side elevation of the cam shown in Figure IV.

Figure VI is a fragmentary sectional elevation illustrating another embodiment of the invention.

Figure VII is a sectional elevation taken on the line VII—VII of Figure VI.

Figure VIII is a detail perspective view of one of the cams shown in Figure VI.

Similar reference numerals refer to similar parts throughout the several views of the drawings.

The automatic take-up device shown and described in the present application as a compensating means for lost motion between the valves and cam shaft of an internal combustion engine may readily be applied to other mechanisms where it is desired to provide compensating means for lost motion between an operating and operated member or members, it being understood that the present application is merely illustrative of one of the uses to which the invention may be put.

Referring to the drawings 10 represents a portion of the cylinder block of an internal combustion engine and 11 the cam shaft of the engine. The valves 12 are provided with the usual valve stems 13 through the lower ends of which are extended the pins 14 for supporting the spring seats 15 carrying the lower ends of the valve closing springs 16, the upper ends of said springs being held by the valve stem guides 17 which are preferably cast integral with the cylinder block. Seated upon the cams 18 of the cam shaft 11 are the heads 19 of the push rods 20, which are reciprocably mounted in the guides 21 of the engine frame or block 10. The upper ends of the push rods 20 are provided with curved or concave faces which are rectangular in outline and which are adapted to receive the correspondingly shaped cams 22 shown in detail in Figure III. The cams are preferably elliptical in form and upon the upper faces thereof are the removable valve stem seats 23 which are recessed to receive the lower ends of the valve stems as shown in section in Figure I, it being understood that the lower faces of the seats are also concave or curved to correspond to the curvature of the cam which is the same on both

sides of its major axis, said cam being normally disposed with its minor axis in a plane parallel to the longitudinal axis of the push rod. Projecting laterally from the valve 5 stem seat and adjacent the top thereof is a recessed arm 24 and beneath the same and extending laterally from the cam 22, substantially parallel to the major axis thereof, is a recessed arm 25. Seated in the recessed 10 portions of these arms is a coiled spring 26 which is considerably compressed when in normal position as shown to the left of Figure I. The arm 25 serves as a lever by which the spring 26 rotates the cam 22 about an 15 axis transverse to the longitudinal axis of the push rod or valve stem, or in a plane parallel to said valve stem axis, it being understood of course that rotation of the cam will be effected only when the parts of the 20 mechanism have become worn or when the valve stems may be raised by the accumulation of carbon on the valves and valve seats. It is understood, of course, that as the parts become worn from time to time and as the 25 upper arm 24 is fixed relatively to the valve stem the spring 26 will shift the major axis of the cam from the normal horizontal position to an inclined position or in other words rotate the cam to take-up or compensate 30 for any lost motion between the valve and cam shaft. This construction affords at all times a solid seat or body of metal between the push rod and valve stem and has a wedging action constantly tending to move 35 the valve stem away from the push rod.

In order to provide lubrication for the wearing surfaces of the cam and seats thereof I have extended through the push rod from a point beneath the cam to a point at 40 one side of the head 19 of the push rod a wick 27 upon which oil from the crank case of the engine may be splashed to be conveyed by capillary attraction to said cam, said wick being tightly drawn into the 45 diagonally extended bore of the push rod as shown at the left of Figure I.

In the modification shown in Figures IV and V I have provided a slightly modified form of cam as indicated at 28, which is 50 seated in a recess in the top of the push rod, said recess being curved to correspond to the curvature of the cam on its lower face opposite the major axis of the cam. A correspondingly curved cam engaging member 55 29 is mounted upon the upper surface of the cam as shown in Figure IV and forms a seat for the valve stem 13. In this modification the cam is provided with a removable arm in the form of a pin 30 which is screwed 60 into the cam and provided with a notch 31 in the outer end thereof to receive the lower end of the coil spring 32, the upper end of said spring being anchored in the notch 33 of the pin 34 which is screwed into the lower 65 end of the push rod 13. The pin 30 when in

normal position is preferably inclined downwardly as shown in Figure IV and the spring is constantly tending to lift the pin 30 for the purpose of rotating the cam 28 to compensate for lost motion between the 70 several parts of the mechanism.

In Figures VI and VII I have shown a double cam arrangement wherein the two cams 35 are placed side by side with their laterally up-turned arms 36 extending in opposite directions and upon opposite sides of the valve stem 13 as shown in Figure VI. In this modification the adjacent ends of the push rod and valve stem are recessed to receive said cams in the manner shown in Figures VI and VII. The arms 36 are preferably bevelled or inwardly inclined as indicated at 37 to receive the lower end of the coil spring 38, the upper end of which is preferably seated upon the pin 14 supporting the spring seat 15. However, the upper end of said spring 38 may be anchored at a point below said pin if desired, to permit the pin to be more conveniently removed from the valve stem. By providing the inclined or bevelled faces on the arms 36 of the cams 35 to form a seat for the lower end of the spring 38, said spring is thereby properly centered around the valve stem and held against lateral displacement in the operation of the cams. It will be understood that as the parts of the mechanism become worn from time to time the spring 38 will automatically rotate the cams 35 in opposite directions to compensate for lost motion between the valves and cam shaft, thereby preventing noise in the operation of the device and assuring accuracy in the lifting of the valves at the proper predetermined time.

Having thus described my invention, what I claim as new and desire to secure by Letters Patent, is:

1. In an automatic take-up device, the combination with two or more members to be actuated, and a spring actuated member interposed between the first mentioned members and rotatable about an axis extending transversely to and intersecting the longitudinal axis of the members to be actuated and tending to move the same in opposite directions.

2. In an automatic take-up device, the combination with two or more members to be actuated, an elliptical member rotatable between said first mentioned members about a fixed axis transverse to the direction of movement of the actuated members and tending to move the same in opposite directions, means for actuating said rotatable member, and means for actuating the first mentioned members independently of the last mentioned actuating means.

3. In an automatic take-up device, the combination with two or more members to be actuated, a plurality of elliptical members

- interposed between said first mentioned members for moving the same in opposite directions, and means for actuating said last mentioned members.
4. In an automatic take-up device, the combination with two spaced members mounted for reciprocating movement, an elliptical cam interposed between the same and movable in a plane substantially parallel to the direction of movement of the reciprocably mounted members, means for actuating said cam, and means for actuating said reciprocably mounted members.
5. In an automatic take-up device, the combination with a plurality of spaced members mounted for reciprocating movement, means for reciprocating the same, independent elliptical cams mounted between said members for rotation in opposite directions to effect movement of said first mentioned members one relatively to another, and means for actuating said cams.
6. In an automatic take-up device, the combination with a plurality of spaced members mounted for reciprocating movement, means for reciprocating the same, independent elliptical cams mounted between said members for rotation in opposite directions to effect movement of said first mentioned members one relatively to another, means for actuating said cams, and means by which lubricating material is supplied to said cams.
7. In an automatic take-up device, the combination with two or more members mounted for reciprocating movement, means for reciprocating the same, means interposed between said reciprocably mounted members adapted to move one relatively to another independently of the reciprocating means, and a wick leading from an oil supply source through one of said first mentioned members to the interposed means for moving said first mentioned members.
8. In an automatic take-up device, the combination with two reciprocably mounted members, an elliptical cam mounted between said members for moving them in opposite directions, said cam having an arm extending therefrom, a yieldable member interposed between said arm and one of said members and means for reciprocating said first mentioned members.
9. In an automatic take-up device, the combination with two reciprocably mounted members, a pair of independent cams mounted between said members for movement in opposite directions to move one of said members relatively to another, oppositely extending arms upon said cams, means engaging the arms to move them in opposite directions, and means for reciprocating said first mentioned members.
10. In an automatic take-up device, the combination with two reciprocably mounted members, a pair of cams mounted between said members for movement in opposite directions, a spring surrounding one of the first mentioned members and cooperating with the cams to move them in opposite directions for the purpose of moving one of the first mentioned members relative to the other, and means for reciprocating said first mentioned members.
11. In an automatic take-up device, the combination with two reciprocably mounted members, a pair of cams mounted between said members and having oppositely extending arms provided with bevelled faces, a spring anchored upon one of said first mentioned members and extending into engagement with the bevelled faces of said arms, and means for reciprocating said first mentioned members.
12. In an automatic take-up device, the combination with two spaced reciprocably mounted members, means for actuating the same, a rotatable cam between said members provided with a laterally extending arm, a spring anchor upon one of said reciprocably mounted members, and a spring between said anchor and said arm tending to rotate said cam in a direction to move said reciprocably mounted members away from each other.
13. In an automatic take-up device, the combination with two spaced members mounted for reciprocating movement, one of which is provided with a lateral projection, a rotatable cam interposed between said reciprocably mounted members, and having a projection thereon a spring interposed between said projections and operatively connected with said cam for rotating the same to compensate for lost motion between said parts.
14. In an automatic take-up device, the combination with the valve stems and push rods of an internal combustion engine each of which is provided with a concave portion, a cam mounted between said valve stem and push rod having convex portions in engagement with said concave portions, means for actuating said cam to compensate for lost motion between said parts, and operating means for said valve stem and push rods.
15. In an automatic take-up device, the combination with the valve stems and push rods of an internal combustion engine, a cam interposed between each of said stems and push rods to compensate for lost motion between the same, springs for actuating said cams, a cam shaft for actuating said push rods, and a wick extending from the cam of each of said push rods into the crank case of the engine in position to receive lubricating material from the crank case when the engine is running.
16. In an automatic take-up device, the combination of two rods mounted end to end.

end, a member disposed between said ends having oppositely arranged convex faces having oppositely arranged convex faces engaging the ends of said rods and means tending to constantly rotate said member between said ends.

17. In an automatic take-up device, the combination of two rods mounted end to end, a member disposed between said ends,

having oppositely arranged convex faces with which said ends engage, an arm extending from said member and a spring connected with the arm and tending to constantly rotate said member between said ends.

In testimony whereof I affix my signature.

FRANCIS JERDONE, JR.
